APPARATUS FOR CENTRIFUGALLY MOLD-
ING CONCRETE PIPES AND OTHER TUBU-
LAR BODIESRalph Williams, Sydney, New South Wales,
AustraliaApplication July 27, 1932, Serial No. 625,071
In Australia September 17, 1931

2 Claims. (Cl. 25—30)

This invention relates to improved centrifugal molding apparatus for the manufacture of concrete pipes and other tubular bodies in which molds containing concrete or like plastic cementitious material are rapidly rotated to form pipes or similar hollow articles by centrifugal action.

An object of the invention is to provide improved centrifugal molding apparatus of horizontal type so constructed as to enable the molds to be safely spun at considerably greater speed than that attainable in apparatus or machines previously constructed. Accordingly, correspondingly increased centrifugal force or compacting action is applied to the concrete or other material in the molds so that the pipes or other articles produced are particularly dense in character and are free from air bubbles and voids or cavities.

Another object of the invention is to provide centrifugal molding apparatus in which generally the manufacture of concrete pipes may be more expeditiously effected, and in which special detachable molds are charged with cementitious material before they are inserted into a rotatable carrier to mold the contained material into the required form.

A further object resides in the provision of centrifugal molding apparatus in which the mold carrier is mounted on adjustable anti-friction bearing rollers and is adapted to receive interchangeable holders for detachable molds of different sizes, and in which a brake is provided to quickly arrest the rotation of the mold carrier when required.

The invention also provides an improved pipe mold adapted to be readily placed in and driven by the rotatable mold carrier and provided with a detachable former shaped to correspond with the interior of a pipe faucet.

In the accompanying explanatory drawing:—

Fig. 1 is a side elevation of centrifugal molding apparatus according to the invention.

Fig. 2 is an end elevation of the molding apparatus.

Fig. 3 is a transverse section of the molding apparatus.

Fig. 4 is a sectional view of a detail.

Fig. 5 is a transverse section of the antifriction bearing roller seen in Fig. 4.

Fig. 6 is a view partly in elevation and partly in section of a pipe mold.

Fig. 7 is a section of portion of a modified pipe mold.

In the drawing, 1 indicates a base or bed plate upon which are fixed axially aligned hollow bearing housings 2. These bearing housings are preferably made in two parts, the lower part 3 being bolted to the base or bed plate 1, and the upper part 4 being detachably secured to

the lower part 3 by bolts 5. The bolts 5 are passed through flanges 6 and 7 formed respectively on the upper and lower parts of the housings 2, and removable shims or liners 8 may be inserted between the flanges 6 and 7 so that the parts 3 and 4 of the housings may be brought more or less closely together.

The bearing housings 2 are of trough-shape or section—see Fig. 4—and mounted on spindles or bolts 9 extending transversely through the housings 2 are anti-friction rollers 10 fitted with ball bearings as shown, or with roller bearings or other type of suitable anti-friction bearings.

The ball bearing rollers 10 are evenly spaced at equal radial distances from the axis of the bearing housings 2 and their inner races 11 are eccentrically mounted upon the spindles or bolts 9 and are non-turnably fixed to the same as by keys 12, see Fig. 5. Accordingly, it will be observed that by turning the spindles or bolts 9 the rollers 10 can be adjusted towards or away from the axis of the housings 2 for a purpose hereinafter referred to. The anti-friction rollers 10 are maintained in a central position in the bearing housings 2 by collars 13 mounted upon the spindles or bolts 9.

The outer races 14 of the ball bearing rollers 10 are encircled with annular hardened wearing bands 15 which fit and roll in peripheral grooves 16 in annular bearing rings 17. These annular bearing rings fit freely in the bearing housings 2 and are disposed peripherally about and fixed to a tubular mold carrier 18.

In Figs. 2 and 3, three anti-friction rollers 10 are shown, the same being evenly disposed about the mold carrier 18, but a greater number of said rollers may be used if required. However, it will be understood that if less than three anti-friction rollers 10 are employed it will not be possible to avoid slackness of the rotatable mold carrier 18 or to spin the same at high speed.

The interior of the mold carrier 18 is provided with mold supports or holders 19 which are bored at 20 to accommodate and accurately centre a mold 21, see Fig. 3. The supports or holders 19 may be conveniently formed as castings, and they may be detachable and interchangeable with others of various sizes, so that molds of greater or less dimensions may be readily accommodated in the mold carrier 18.

The mold 21 (shown separately in Figs. 6 and 7) is preferably made in two semi-cylindrical portions or halves 22 and 23 having angle strips 24 fixed along their edges. The two halves or semi-cylindrical portions 22 and 23 are secured together to form the mold 21 by bolts 25 passing through the adjoining angle strips 24.

In order to permit the mold 21 to be inserted into the mold carrier 18 and to provide a driving connection between the latter and the former,

the holders or castings 19 are provided with opposed radial slots 26. These radial slots accommodate the angle strips 24, and the edges of said slots by contact with the angle strips provide a 5 positive driving connection between the mold carrier 18 and the mold 21 and prevent independent rotation of the latter and the former.

The mold 21 at one end may be provided with an angle ring or internal flange 27 forming a 10 circular opening 28 of somewhat less diameter than the interior of the mold 21.

The opposite end of the mold 21 may be provided with an enlargement 29 shaped to correspond with the external contour of a pipe faucet. 15 Detachably fitting the exterior of the enlargement 29 is an annular member or former 30 shaped to form the interior of the pipe faucet.

The annular member 30 may be secured to the enlargement 29 by a bayonet slot 31 made in the 20 former and adapted for engagement with a projecting pin 32 fixed in the latter. Alternatively, the detachable annular former 30 may be fixed to the enlargement 29 by wing nuts 33 or other suitable fastenings.

25 In practice, the two halves 22 and 23 of the mold 21 are oiled and assembled by the bolts 25, and the mold is then placed on end with the faucet enlargement 29 downwards, the annular former 30 being suitably plugged. Sufficient 30 concrete or other cementitious material to form a pipe of required thickness is then placed in the mold 21 and the opening 28 is suitably plugged. The charged mold 21 is then placed in position in the mold carrier 18, and the latter is 35 set in rotation, preferably by a driving belt 34 applied to its periphery.

The mold carrier 18 with the mold 21 therein is then slowly rotated for a short period to enable the concrete to become evenly distributed 40 over the inner surface of the mold. The speed is then increased and the mold 21 is rotated for a sufficient time at high speed to consolidate the concrete material.

45 Trowelling means of well-known construction quickly run over the interior of the pipe during the formation to withdraw the water and slurry separated by the compacting centrifugal action and to render the surface of the finished pipe hard and smooth.

50 A brake is provided to enable the rapidly rotating mold carrier 18, mold 21 and the pipe therein to be quickly brought to rest, when required. The brake may be of any suitable construction and hand or foot operated, and it may 55 comprise a post 35 fixed to the base 1 and provided with a lever 36 and brake shoe 37 to be applied to the periphery of the mold carrier 18 by manual operation.

60 The interior of the bearing housings 2 may be subdivided into chambers 38 by transverse partitions 39 positioned adjacently to and on opposite sides of the anti-friction rollers 10. The said chambers 38 may be packed with suitable semi-fluid lubricant and they may be provided with lubricating devices 40. Accordingly, 65 the anti-friction rollers 10 and the annular bearing rings 17 are at all times efficiently lubricated, thereby ensuring silent and smooth operation and minimizing wear.

70 At the conclusion of the spinning operation, the mold carrier 18 is stopped by the brake shoe 37, and the mold 21 is removed and set aside for

a sufficient time to permit the concrete material to properly set and harden. The annular faucet member or former 30 is then removed and the bolts 25 are withdrawn, thereby permitting the semi-cylindrical portions 22 and 23 to be taken 80 from the finished pipe.

Owing to the high speed made possible by the anti-friction rollers 10 and the efficient lubrication, the finished pipe is very dense, smooth and hard. Moreover, it may be readily removed from 85 the mold 21 without steaming, and generally in about five hours after the termination of the spinning operation, thereby permitting the molds 21 to be used twice daily.

The adjustable feature of the ball bearing 90 rollers 10 previously described enables the mold carrier 18 to be accurately centered in each of the bearing housings 2, so that it may spin with minimum frictional resistance and without shake or looseness. Moreover, by adjustment of the 95 rollers 10 and removal of one or more of the liners or shims between the lower part 3 and the upper part 4 of the bearing housings 2, wear of the rollers 10 and annular rings 17 may be compensated for and correct alignment of the 100 mold carrier 18 and bearing housings 2 may be permanently maintained.

It will be understood that as the concrete material is placed in the mold 21 before the commencement of the spinning operation, the 105 undesirable reduction of the water content brought about when the material is thrown in shovelfuls into the rotating mold is obviated.

What I do claim is:—

1. A centrifugal molding apparatus including 110 a base, a plurality of two-part annular housings carried by the base, one part of each of said housings being fixed to the base, the remaining part of each of said housings being adjustably connected to the fixed part, ball bearing supports mounted in the respective parts of each housing, a mold carrier arranged within each housing and rotatably supported on the ball bearing supports therein, one of said ball bearing supports being eccentrically mounted for 115 adjustment toward and from the mold carrier, each ball bearing support including an annular member removably mounted on the ball bearing support and forming the bearing for direct contact with the mold carrier, and an element on 120 the mold carrier disposed in an open inner periphery of each annular housing to provide bearing contact with the removable member of the ball bearing.

2. A centrifugal molding apparatus including 125 a base, a rotating mold carrier, an annular housing encircling the carrier adjacent each end thereof, each housing comprising a part fixed to the base and a second part adjustably connected to the fixed part, the parts of the housing 130 being formed with chambers opening toward the carrier, a ball bearing in each of said chambers, means for eccentrically mounting at least one of said ball bearings to provide for its adjustment toward and from the carrier, said ball bearings 135 including an annular separable member forming the contacting element between the bearing and carrier, and an annular member secured to the carrier and formed with a channel to receive said separable member.
